UNITED STATES PATENT OFFICE.

IRVIN L. YOUNG, OF CHICAGO, ILLINOIS.

ENVELOP-MAKING MACHINE.

1,270,581.

Specification of Letters Patent. Patented June 25, 1918.

Application filed October 16, 1917. Serial No. 196,873.

To all whom it may concern:

Be it known that I, IRVIN L. YOUNG, a citizen of the United States, residing at Chicago, in the county of Cook and State of Illinois, have invented new and useful Improvements in Envelop-Making Machines, of which the following is a specification.

This invention relates to machines for making envelopes of that type generally known as "window" envelopes, the same having an opening in that portion which is to receive the address, this opening being covered by a sheet of transparent paper, so that the address, suitably written on the inside of the envelope, will be displayed through said covering or "window."

The invention has for its object to provide in a machine of the kind stated, a novel and improved means for applying the transparent sheet or "patch", as it is termed in the art, and to this end, the invention consists in a combination and arrangement of parts to be hereinafter described and claimed, reference being had to the accompanying drawings forming a part of this specification.

In the drawings,

Figure 1 is an elevation of that portion of the machine with which the "patch" applying mechanism is associated, parts being shown in section;

Fig. 2 is a section on the line 2—2 of Fig. 1;

Fig. 3 is an enlarged section on the line 3—3 of Fig. 2;

Fig. 4 is an inverted plan view of a "patch" severing device;

Fig. 5 is an elevation of a plunger as viewed from the left in Fig. 3, and

Fig. 6 is an elevation of the plunger as it appears when in the dotted line position in Fig. 1.

Referring specifically to the drawings, the invention is applied to a machine in which a previously formed envelop blank is folded by being forced by a reciprocating plunger into a folding box. The envelop blank has an opening whose margin has a fresh coating of paste to receive the "patch", and the latter is fed to the plunger so that the patch is applied at the same time the envelop blank is folded. The folding box is shown at 10, and the plunger at 11, the latter being carried by a stem 11^a. The mechanism for operating the plunger has not been illustrated as it forms no part of the present in-

vention, and for the same reason the paste-applying and other elements of the machine have not been shown. The drawings illustrate only so much of the machine as will suffice for an understanding of the invention.

At 13 is shown a roll of patch stock, the latter being led down between a feed roll 14 and a pressure roll 14^a. Frame members 15 carry a cross bar 15^a which carries on its under side a stationary shear blade 16 and a movable blade 17 co-operating therewith. A ratchet 18 on the shaft of the roll 14 is operated by a pawl 19 actuated by a rocker arm 20 having an extension 21 operatively connected to the shear blade 17. The pawl 19 therefore periodically feeds the web of patch stock, and at each feeding movement the blade 17 is operated to cut off a patch from the web. The actuating means for this patch feeding and cutting mechanism will be presently described.

Beneath the cutting mechanism is located a holder plate 22 which receives the cut off patch dropped by the shears, this plate being pivotally hung on a shaft 23 extending between and supported by the frame members 15. The plate 22 normally hangs pendent as shown dotted in Fig. 3, but swings toward a patch carrier 24 when the latter strikes lugs 25 on the plate. These lugs carry a transverse shaft 26 on which are mounted two spring fingers 27 to prevent the patch from falling off the plate 22 while the latter hangs in pendent position. The spring fingers are spaced from the face of the plate 22 and their lower free ends seat on an outstanding marginal flange 22^a at the bottom of the plate. The patch is delivered to the plate beneath the spring fingers, and the latter, with the flange 22^a, serve to retain the patch on the plate. Where the plate 22 engages the patch carrier 24, the latter has grooves 28 to accommodate the guard or retaining fingers 27, the patch being shorter than the distance between the grooves.

The carrier 24 is pivoted at 29 to the plunger 11 and has an arm 30 carrying a roller 30^a traveling in a cam slot 31 of a stationary member 32.

The plunger stem 11^a has spaced side pins or abutments 34 between which the pawl-actuating lever arm 20 extends. The plunger stem reciprocates, and on the down stroke the upper pin swings the arm 20 to actuate the pawl, whereby the web of patch

stock is fed and a patch is cut off as hereinbefore described. On the up stroke, the bottom pin returns the arm 20 for the next stroke.

5. The plunger stem 11^a is supported in bearings 35 having side slots 36 to permit the pins 34 to pass.

The patch carrier 24 is hollow and has a plane face provided with perforations 37, 10 and a flexible hose 38 leading from a suitable suction producing device, is connected to the patch carrier, the interior thereof being a suction chamber. The patches are delivered to the perforated face of the carrier and are held by the suction at the perforations 37. The carrier is pivotally connected to the plunger 11 at one end thereof, and it is so positioned and dimensioned that when it is in delivering position, its patch-carrying, 15 perforated face is flush with the bottom or working face of the plunger. A spring 39 coiled around the pivot 29 of the carrier and pressing against the latter tends to swing the same toward the plunger to bring 20 its perforated face flush with the bottom of the plunger when the roller 30 clears the cam slot 31.

At the beginning of the working stroke of the plunger 11, the roller 30^a is at the 25 inner end of the cam slot 31, and the carrier 24 has swung away from the plunger, so that its perforated face is now opposite to, and facing the patch holding plate 22. The suction in the carrier causes the patch to adhere 30 to the perforated face of the carrier, and the plunger now descending, the cam slot 31, through the roller 30^a, swings the carrier away from the plate 22 and toward the plunger. As the roller clears the cam slot, 35 the spring 39 closes the carrier up against the plunger so that the perforated face holding the patch is now flush with the plunger bottom. The plunger, with the carrier in this position, continues its descent and enters the folding box 10, as shown dotted in 40 Fig. 1, whereupon³ the envelop blank is folded, and the patch is applied at the same time, it being understood that the suction will be cut off at the proper time to release 45 the patch. On the return stroke, the roller 30 again enters the cam slot 31, whereby the carrier is caused to swing back toward the holder 22 to receive another patch. As the carrier approaches the holder, it strikes 50 the lugs 25 and swings the holder from the dotted line position to the full line position in Fig. 3. The holder 22 is normally in pendent position as shown dotted, and it receives the patch in this position. The operation 55 of the patch feeding and cutting mechanism is timed to deliver a patch to the holder at the proper time.

I claim:—

1. In an envelop making machine, a reciprocatory blank-folding plunger, a pivoted

patch carrier mounted on the plunger, means for swinging the patch carrier outward from the plunger to patch-receiving position and alongside the plunger into patch-delivering position, said carrier, while in the last mentioned position having its portion which carries the patch flush with the working face of the plunger, and means for delivering a patch to the carrier when in receiving position. 70

2. In an envelop making machine, a reciprocatory blank-folding plunger, a pivoted patch carrier mounted on the plunger, means for swinging the patch carrier outward from the plunger to patch-receiving position and alongside the plunger into patch-delivering position, said carrier, while in the last mentioned position having its portion which carries the patch flush with the working face of the plunger, a pivoted patch holder, 80 means for feeding patches to said holder, and means for swinging the holder toward the carrier when the latter swings to receiving position. 75

3. In an envelop making machine, a reciprocatory blank-folding plunger, a pivoted patch carrier mounted on the plunger, means for swinging the patch carrier outward from the plunger to patch-receiving position and alongside the plunger into patch-delivering 90 position, said carrier, while in the last mentioned position having its portion which carries the patch flush with the working face of the plunger, a pivoted patch holder, 95 means for feeding patches to said holder, and means for swinging the holder toward the carrier when the latter swings to receiving position. 100

4. In an envelop making machine, a reciprocatory blank-folding plunger, a pivoted patch carrier mounted on the plunger, means for swinging the patch carrier outward from the plunger to patch-receiving position and alongside the plunger into patch-delivering 110 position, said carrier while in the last mentioned position, having its portion which carries the patch flush with the working face of the plunger, means for delivering a patch to the carrier when in receiving position, and suction means associated with the carrier for holding the patch thereon. 115

5. In an envelop making machine, a reciprocatory blank-folding plunger, a pivoted patch carrier mounted on the plunger, means for swinging the patch carrier outward from the plunger to patch-receiving position and alongside the plunger into patch-delivering position, said carrier while in the last mentioned position, having its portion which carries the patch flush with the working face of the plunger, a pivoted patch holder, means for feeding patches to said holder, means for swinging the holder toward the carrier when the latter swings to receiving position, and 120 125 130

suction means associated with the carrier for holding the patch thereon.

6. In an envelop making machine, a reciprocating blank-folding plunger, a pivoted patch carrier mounted on the plunger, means for swinging the patch carrier outward from the plunger to patch-receiving position and alongside the plunger into patch-delivering position, said carrier while in the last mentioned position, having its portion which carries the patch flush with the working face of the plunger, a patch holder, suction means associated with the carrier for taking the patches from the holder and retaining the same on the carrier, and means for feeding patches to the holder.

7. In an envelop making machine, a re-

ciprocating blank-folding plunger, a pivoted patch carrier mounted on the plunger, means for swinging the patch carrier outward from the plunger to patch-receiving position and alongside the plunger into patch-delivering position, said means comprising an arm projecting from the carrier and having an abutment, and a cam slot in a part stationary relative to the plunger in which slot the abutment seats, said carrier while in the last mentioned position having its portion which carries the patch flush with the working face of the plunger, and means for delivering a patch to the carrier when in receiving position.

In testimony whereof I affix my signature.

IRVIN L. YOUNG.
